UNITED STATES PATENT OFFICE.

BERT B. MILNER, OF NEW YORK, N. Y.

TRAIN-RESISTANCE-COMPUTING MEANS.

1,210,515.

Specification of Letters Patent.

Patented Jan. 2, 1917.

Application filed January 8, 1915. Serial No. 1,080.

To all whom it may concern:

Be it known that I, BERT B. MILNER, a citizen of the United States, residing at New York city, borough of Manhattan, in the county of New York and State of New York, have invented certain new and useful Improvements in Train-Resistance-Computing Means, of which the following is a specification.

10 My invention relates to new and useful improvements in computing devices, and particularly contemplates a simple and accurate device for computing the adjusted tonnage of a train, so that the size of a train; 15 that is, the number of cars offering a uniform amount of resistance to movement, may be as quickly and accurately determined as gross weights, whether the train be composed of loaded cars or empty cars, or any 20 combination thereof, so that a train may be accurately made up having a resistance corresponding to and absorbing the pulling capacity of any locomotive selected to haul the same. 25 It is well known that trains composed of empty or lightly loaded cars offer greater amounts of resistance to movement per ton of weight and less amounts of resistance to movement per car than trains of more heavily loaded cars. Therefore, a locomotive can 30 haul a greater number of cars in trains composed of empty or lightly loaded cars than in trains composed of more heavily loaded cars, but can haul a greater number of tons 35 in trains composed of heavily loaded cars than in trains composed of more lightly loaded or empty cars. It follows from the above that a train of cars cannot be made up to the hauling capacity of a given locomotive by merely "measuring out" trains upon 40 the basis of a uniform number of either cars or tons. This is also true because of the further fact that, while a given number of heavily loaded cars may fully load any given 45 locomotive to its hauling capacity under any given condition of grade and track alignment, the same number of more lightly loaded or empty cars will not load the same locomotive to capacity and trains so constituted will be "light" or fail to utilize the 50 hauling capacity of the locomotive with obvious corresponding loss, and, while a given number of tons in empty or lightly loaded cars may fully load the same locomotive, the 55 same number of tons in more heavily loaded cars will not load the locomotive to capacity,

and, as under the former conditions, trains so constituted will not load the locomotive to capacity.

It has been established within practically negligible limits, that the resistance of freight trains is separable into two parts or factors—*i. e.*, one proportional to the weight of the train (largely, though not entirely, the resistance due to grade), and the other proportional to the number of cars in the train (largely, though not entirely, the frictional resistance due to mechanical parts of the cars, such as journals, etc.). From this the following quoted equation has been employed to express the relation existing between the hauling capacity of a locomotive and the train resistance:

$$P = fW + cN,$$

in which equation P expresses the tractive power of the locomotive at the required speed. f denotes that part of the resistance proportional to the weight of the train per ton. W denotes the weight of the train in tons. c denotes the remaining resistance per car. N denotes the number of cars in the train. In using this equation so as to make it practicable in freight yard offices for the determination of the cars for each train despatched this equation has been divided through by f , so as to read

$$\frac{P}{f} = W + \frac{c}{f}N,$$

in which $\frac{P}{f}$ for a given locomotive under known conditions of track grade and alignment is a constant, but for various locomotives with the same conditions of track grade and alignment is a variable proportional to the hauling capacity of the various locomotives. In

this last equation $\frac{c}{f}N$ is the number of cars (N) multiplied by $\left(\frac{c}{f}\right)$ a constant under given track conditions which is determined by calculation or experiment.

In practice the expression $\frac{P}{f}$ is employed in freight yard offices as designating "train ratings" in "adjusted tons" and these offices make up trains of the proper number of cars and tons to make the expression $W + \frac{c}{f}N$, equal the "adjusted tons" designated in the

train ratings. The practice generally used in accumulating the adjusted tonnage of any train, is to add cars to the train until the adjusted tonnage, obtained by adding

- 5 the constant $\frac{e}{f}$, which, under summer weather conditions, varies from approximately 5 to 50 dependent upon track grade and alinement, and, under lower temperature and other adverse weather conditions, is higher, to the weight of each car in tons as added to the train, until the total equals that quoted as the hauling capacity of the locomotive which is to haul the train.
- 10 The primary object of the invention is, therefore, to provide a simple and accurate device which will enable the operator making up a train to total the gross ton weights of a number of cars, and to automatically add to the gross ton weight of each car a number of tons which is a constant for and determined upon basis of the track conditions over which the train is to travel and substantially uniform temperature and other weather conditions affecting train resistance.
- 15 A further object of the invention is to provide means whereby the constant added to the gross weight of each car may be easily increased by the person operating the machine from that determined for summer weather conditions to the higher constant required by lower temperature or other adverse weather conditions.
- 20 The invention consists in the improvements to be more fully described hereinafter and the novelty of which will be particularly pointed out and distinctly claimed.
- 25

I have fully and clearly illustrated one embodiment of my invention in the accompanying drawings to be taken as a part of this specification and wherein:

Figure 1 is a top plan view of one embodiment of my invention. Fig. 2 is a sectional view on the line 2—2 of Fig. 1. Fig. 3 is a detail sectional view on the line 3—3 of Fig. 1. Fig. 4 is an enlarged plan view partly in section, with parts removed, of certain of the operating parts shown in Figs. 1 and 2.

Referring to the drawings by characters of reference: 1 designates a base plate, formed of two substantially circular parts 2, 3, rigidly connected to each other, said plate being surrounded by a peripheral upstanding flange or rib 4, each of said parts 2, 3, having an inner upstanding flange shown, respectively, at 5 and 6, concentric with said parts and each forming with said surrounding flange 4 an annular pocket in each of said parts.

In the present embodiment the part 2 is made of larger diameter than the part 3, and has associated therewith indicating

mechanism to add ton weights of cars in 65 units and tens while the part 3 has associated therewith mechanism for indicating hundreds resulting from continued operation of the units and tens mechanism. I will now describe these mechanisms:

Rotatably arranged in the pocket in the part 2 is a circular disk 7 having a central opening receiving the flange or boss 5, heretofore mentioned. The outer edge of this disk 7 preferably rests upon a ridge or shoulder 8 on the inner face of the flange 4, and is covered and retained in position by a cover ring 9 surrounding said edge and secured to the flange 4 by fastening screws 10. The outer edge of the disk 7 is equally divided into two segments 11, 12, respectively, each being provided with a series of one hundred equi-distant pockets or recesses 13, 14, respectively, adapted to receive a pencil or other pointed instrument whereby 85 said disk may be rotated. The ring 9, heretofore described, is provided with two scales 15, 16, to coöperate respectively with the pockets 13, 14, heretofore described, said scales being marked to correspond with said 90 pockets and indicating amounts from one to one hundred extending oppositely from a zero point 17 to a zero point 18, said zero points being at diametrically opposite points on the said ring 9. The pockets on the segments 11, 12, are numbered with scales respectively from 1 to 99, as at 7^a, and a zero mark, which scales, as the disk is rotated, are displayed through a sight opening 9^a in the ring 9. It will be understood that 95 these scales extend at quarters from the scales 15 and 16, so that the scales 7^a will appear at said opening when the disk is moved to the zero point 17 of the scale 15.

The scale 15 described is employed to indicate gross ton weights of the cars to make up a given train—that is, the ton weight of the car plus the ton weight of the load carried by the car, this amount being designated by the scale 15 when turned clockwise up to and when stopped at the zero point 17, it being noted that the scale 15 progresses from one to one hundred in a direction counter-clock-wise of the ring 9. That is, the distance between the zero points 115 17, 18, is proportional to that portion of the total train resistance which exists on account of grade.

The scale 16 is employed for adding to the ton weight of each car, as added to ton 120 weights of other cars, an amount equal to the constant $\frac{e}{f}$, heretofore referred to, said scale progressing clock-wise from the zero point 17 to the zero point 18, so that 125 the total will include the total train resistance. In order to accomplish this result, the disk 7 is rotatable clock-wise past

the zero point 17, and stopped at a point at a distance to the right of said point sufficient to add to the car tonnage the constant desired, and an adjustable stop is provided 5 for properly fixing the stopping point of the disk. This stop may consist of a plate 19 having a stop-arm 20, adapted to project inward over the outer edge of the disk 7 and the pockets therein, said arm acting as an 10 abutment to be engaged by the pencil or other instrument by which the plate 7 is rotated. For purposes of adjustment the plate 19 may be formed with slots 21 to receive fastening screws 22 adapted to be threaded 15 into sockets 23 arranged in the flange 4 circumferentially of the ring 9 and arranged opposite points five spaces apart on the scale 16. By this arrangement the stop may be located at any point clock-wise of the scale 20 16 between the zero points 17 and 18, the slots 21 permitting adjustment to the individual scale marks.

In Fig. 1 the stop is shown fixed at 10 on the scale 16 so that any car of weight indicated by the scale 15 will have added to it the amount proportional to the space between the zero mark 17 and the stop 20—that is, the constant 10 will be added to each 30 car's gross weight. By this means the total at the opening 9^a will indicate "adjusted tons" proportional to the total train resistance, and can be accumulated until it properly approximates the load-pulling capacity of a given locomotive as reflected in 35 its "adjusted tonnage" rating.

In the part 3 is an indicator disk 24 for amounts over 100 or multiples thereof, which disk is provided with a scale of numbers indicating hundreds which are adapted 40 to be individually displayed at the opening 9^a. This disk is adapted to be rotated by any suitable mechanism from the disk 7, whenever the latter has made one-half a revolution. This may be accomplished by any 45 suitable well-known mechanism for the purpose; such, for instance, as that shown in dotted lines in Fig. 1 and in full lines in Fig. 3. In this construction the disk 7 is provided with a collar 25 having two recesses 26 spaced to correspond to the scales, and coöperating with surface of said collar is a pivoted dog 27 which is engaged by the rear end 28 of a sliding pawl 29, the nose of which is adapted to coöperate with ratchet 55 teeth 30 on the under side of the disk 24. The pawl and dog are urged toward the collar 25 by means of a spring 31 so that, when one of the recesses 26 reaches the dog, the latter, and the pawl, will be thrown by 60 said spring toward the recess to cause the pawl to move the disk 24 one space of the scale thereon. As this construction is well-known, I do not consider it necessary to make a more detailed description thereof.

In order to ascertain the adjusted tonnage of a train by the device described, the adjustable stop 19 is fixed so as to stop the clock-wise movements of the disk 7 at a point opposite the scale number on the scale 16 corresponding to the ascertained constant or "adjustment factor"—i. e., the number of tons which must be added to the weight of each car to arrive at an adjusted number of tons proportional to the resistance which the train offers to movement. 65 After the stop 19 has been adjusted in proper position corresponding to the adjustment factor to be used, and the machine is cleared—i. e., brought to show "000" at the opening 9^a, the desired adjusted tonnage 70 is accumulated as follows: The steel pencil is inserted in the pocket 11 on the disk 7, which is opposite the indication on the scale 15, showing the proper gross weight in tons of the first car to be included in the train. 75 The disk 7 is then rotated clock-wise until the pencil abuts the stop lug 20 on the stop 19, which will cause a number to appear at the opening 9^a indicating the adjusted tonnage for that car. This operation is continued car by car until the total adjusted tonnage of the train is registered at 9^a.

The following statements, based upon actual conditions obtaining upon a selected division, illustrate the advantages derived 85 from having attained the objects of the invention. On this division trains were loaded to 2900 gross tons, or as near thereto as possible, as shown by Statement No. 1 for three trains Nos. 1, 2 and 3, composed of 100 lighter (48 ton) medium (58 ton) and heavier (68 ton) cars, respectively.

Statement No. 1.

Train No.	Average weight of cars.	On basis of 2,900 gross tons rating.		(Summer weather and temperature conditions assumed.)	105
		Tons.	Cars.		
1.....	48	60	2,880	Train overloaded although slightly under 2,900 tons.	110
2.....	58	50	2,900	Train properly loaded.	
3.....	68	43	2,924	Train underloaded, although slightly over 2,900 tons.	

The grades and track alignment were such that the train No. 2 of 2900 gross tons in 50 cars weighing an average of 58 tons each neatly absorbed the capacity of the locomotive provided. Train No. 1 was overloaded and train No. 3 was underloaded to the extent of requiring the use of an adjustment 115 factor $(\frac{c}{f})$ of 30 and an adjusted tonnage rating of 4400 adjusted tons, to equate the resistance of trains composed of cars of various weights in order to enable them to 125 equally absorb the capacity of the locomotive provided. Statement No. 2 shows the resulting changes, and it will be noted that

the previously overloaded train No. 1 of 2880 gross tons in 60 cars weighing 48 tons each has been reduced to 2688 gross tons in 56 such cars, while the underloaded train 5 No. 3 of 2924 gross tons in 43 cars weighing 68 tons each has been increased to 3060 gross tons in 45 such cars.

Statement No. 2.

Train No.	Averages per car.			Total adjusted tonnage.	Num-ber cars in train.	Gross tons in train.	(Summer weather and temperature condition assumed.)
	Gross tons.	Fac. for—	Adj-usted tons.				
15	48	30	78	4,368	56	2,688	Train properly loaded.
2.....	58	30	88	4,400	50	2,900	Train properly loaded.
3.....	68	30	98	4,410	45	3,060	Train properly loaded.

20 It will be readily understood that a decrease in temperature or other adverse weather conditions will not affect that portion of resistance (f) proportional to the 25 weight of the train (that due to grades),

but will increase the remaining portion of the resistance (c) so largely constituted of journal friction which is affected materially and promptly by changes in the viscosity of lubricants as result of temperature change. 30

The constant $(\frac{c}{f})$ previously referred to as having to be added to the gross weight of each car in accumulating the "adjusted tons" of a train is increased by lowered temperature or other adverse weather conditions. 35

Statement No. 3 shows the advantage of having attained the second object of my invention referring thereto, while a 24 per 40 cent. reduction in the gross tonnage of train No. 2 is satisfactory in that, with this reduction, the train continues to absorb the capacity of the locomotive, the same reduction in train No. 1 and train No. 3 are insufficient and too great respectively. In other words, after this alteration, the original overload under gross tonnage loading of train No. 1 is augmented; likewise the underload of train No. 3. 50

Statement No. 3.

(Adverse temperature and other weather conditions requiring a reduction of 24% in the size (cars and tons) of trains composed of cars averaging 58 tons weight.)

Train No.	Av. wt. per car.	Gross tonnage ratings.				With 24% reduction in adj. tonnage.			With increase in adj. factor from 30 to 58.		
		Summer.		24% reduction.							
		No. cars.	Gross tons.	No. cars.	Gross tons.	No. cars.	Gross tons.	Adj. tons.	No. cars.	Gross tons.	Adj. tons.
1.....	48	60	2,880	46	2,208	43	2,064	3,354	41	1,968	4,428
1.....	58	50	2,900	38	2,204	38	2,204	3,304	38	2,204	4,408
3.....	68	43	2,924	33	2,204	34	2,312	3,332	35	2,380	4,410

55 This situation is only relieved by applying a 24 per cent. reduction to the 4400 adjusted tonnage rating and loading trains according thereto but removed by maintaining the 4400 adjusted tonnage rating and 60 increasing the adjustment factor from 30 to 58. This gives for train No. 1, 1968 gross tons in 41 cars weighing 48 gross tons each against 43 when adjusted tonnage is reduced 24 per cent., or against 46 where gross 65 tonnage (2900) is reduced 24 per cent., all over 41 cars being an overload. It also gives for train No. 3, 2380 gross tons in 35 cars weighing 68 gross tons each against 34 and 33 where adjusted (4400) or gross 70 (2900) tonnage is reduced 24 per cent., all under 35 cars being an underload.

What I claim and desire to secure by Letters Patent of the United States is:—

1. A device for computing adjusted train 75 resistance or adjusted tonnage proportional

thereto, comprising a rotatable member having a plurality of equally spaced recesses therein, and two circumferential fixed scales coöperating therewith, one indicating car weights, and the other adjustment factors, said scales being numbered in opposite directions from a point common to both, a manually adjustable stop coöperating with the adjustment factor scale, and manually operated means for fixing said stop relative to the adjustment factor scale throughout an indeterminate number of operations of the rotatable member. 80

2. A device for computing adjusted train resistance or adjusted tonnage proportional thereto, comprising a rotatable disk having two hundred recesses therein, two circumferential scales of one hundred divisions each corresponding to the recesses on said disk, one indicating car weights and the other an adjustment factor, a manually ad- 90

95

justable stop coöperating with the adjustment factor scale, and manually operated means for fixing said stop relative to said adjustment factor scale throughout an indeterminate number of operations of said disk.

In testimony whereof I have hereunto

signed my name in the presence of two subscribing witnesses.

BERT. B. MILNER.
